EDWIN J. MILLER, OF ANDERSON, INDIANA

MOP USING REMOVABLE SPONGE OR THE LIKE

Application filed October 12, 1931. Serial No. 568,238.

My invention relates to mops, the washing element of which may be removed and replaced and more particularly to mops in which a mop handle is provided with a clamp head which may be readily operated to engage or release a mopping sponge or the like as desired, and my device consists substantially in construction, combination, and arrangement of parts hereinafter set forth and pointed out more particularly in the accompanying claims.

An object of my invention is to provide a mop having clamping jaws which extend well beyond the mop handle proper and to provide a lever on the handle for manipulating said jaws a sufficient distance from the jaws to be operated without making it necessary for the operator to bring his or her hands near the mopping element.

It is a primary object of my invention to provide a mop handle and head of this class suitable for use with a sponge or the like.

It is a further object of my invention to provide a comparatively light sponge clamping mechanism amply braced and constructed to retain a sponge in operating position.

It is also an important object of my invention to provide a means for clamping a sponge to a handle in such a manner that free access may be had to the sponge for manually squeezing or wringing the mopping fluid from same.

The above and other objects are obtained by the structures illustrated in the accompanying drawings in which,

Figure 1 is a plan view of the mop clamping means and handle as taken when the assembled device is lain flat like on a floor or the like, the sponge clamping jaws being in closed position.

Fig. 2 is a side elevation of the device showing the clamping jaws in closed position, the sponge element being indicated in dotted lines.

Fig. 3 is a view taken from the same viewpoint as Fig. 2, showing the sponge clamping jaws in open position, and the sponge removed.

Fig. 4 is an end view of the device as

projected from Fig. 3.

Fig. 5 is a sectional view taken in the proximity of line 5-5, Fig. 1, and,

Fig. 6 is a sectional view taken in the proximity of line 6-6 of Fig. 2.

Similar characters of reference designate similar parts throughout the views. Referring to Fig. 1, the numeral 1 indicates a conventional wood mop handle upon which the remainder of the device is mounted. Numeral 2 designates a socket which is disposed over the head end of the mop handle, the bracket 3 being formed on the lower portion of said socket and extending forwardly, the width of said bracket increasing forwardly for co-adjoining with the somewhat triangular and relatively stationary jaw member 4. Said jaw member is conveniently formed from a metal rod, the ends of which extend convergingly to and unite with the bracket 3, said bracket having its outer edges 5 bent over the ends 6 of the jaw forming rod, by which said stationary jaw is secured in place. Said jaw is also soldered or otherwise conveniently secured to said bracket.

As above indicated the stationary jaw member 4 is a triangular formation, the forward side 7 of the triangle thus formed being transverse to the trend of the handle 1, and serving as the principal gripping portion of the jaw. The other sides of the triangle thus formed are merged with the forward side 7 of the triangle by arcular bends 8 which also serve with the forward portions of the other sides of the jaw in gripping the sponge 9 or other mopping material.

The rearward portion of the socket 2 is round and conforms the shape and size of the diameter of the handle 1, but the forward portion of said socket is somewhat half-circular in cross section as indicated in Fig. 6, and the upper forward portion of the handle is cut away, so that it may also enter the half-round part of the socket, as well as the rearward portion.

The upper wall of the half-rounded portion of the socket is composed of two sections 10 which extend somewhat horizon-

tally and inwardly for a distance and then upwardly at right angles to the remainder of said sections forming spaced vertical walls 11.

5 The upper jaw 12 of the device mates with the stationary jaw 4 and corresponds in triangular shape and arrangement therewith. The sides of said upper jaw, however, which extend convergingly toward the 10 handle merge with parallel stems 13 which together straddle the vertical walls 11, for a distance, and end with inward right angular bends, the terminations 14 of which pivot through holes in said walls and thus form 15 a pivot upon which the upper jaw is swung into closed position, as indicated by Fig. 2 and to open position as indicated by Fig. 3.

Adjacent the stems 13 the adjoining 20 sides of the upper jaw 12 are tied together with a metal strip 15 which is conveniently bent around said sides, and soldered or otherwise secured thereto. From the rear side of said strip, a branch 16 thereof, extends to between the vertical walls 11, and 25 is pivoted around the extreme inner stem terminations. A V shaped flat spring 17 is nested in the crotch thus formed by said branch and the handle 1, the lower end of said spring being bent downwardly and lodged between the extreme end of said handle and the adjacent portion of the bracket 3, and the upper end of said spring being exerted against the branch 16. By 30 this arrangement it will be understood that the spring 17 serves to move the upper jaw 12 to open position when released as will be understood.

When the upper jaw 12 is in closed position as shown in Fig. 2, the expansion coil 40 spring 18 encircles the socket 2 and the stems 13 and thus holds the two jaws together. When the spring 18 is compressed from engagement with the stems 13, the flat 45 spring 17, being tensioned against the branch 16 of the strip 15 which is secured to said upper jaw as above described, said jaw is swung open by said flat spring on the point formed by the stem terminations, and the corresponding holes in the vertical 50 walls 11.

The coil spring 18 is brought to and held in compressed position for releasing the jaws by manipulation of a dually formed 55 toggle 19 which straddles the handle 1, from above and is pivoted to the socket 2 and handle 1 at points 20. A pair of levers 21 form a part of said toggle and extend downwardly as considered in Fig. 2 approximately a distance corresponding to the 60 amount said coil spring is to be compressed to clear the stems 13 of the jaw 12. The lower extremities of said levers are pivoted to drag links 22, the other ends of said links being hooked over the forward end of said 65 coil spring. It will then be seen that when

the toggle 19 is manipulated to swing the levers 21, rearwardly, a distance of approximately ninety degrees, said coil spring will be compressed to release the jaw 12, as desired. The back of said toggle extends 70 rearwardly along the upper side of the handle 1 for a distance suitable to provide a convenient handle for operating the levers 21, and the handle thus formed is turned 75 up from the handle 1 at its rearward end for convenience in operation.

A stop 23 is formed on the upper part 80 of the toggle 19 which bears against the coil spring 18 when said toggle is swung into position indicated in Fig. 3, said stop being so located as to stop the movement of said toggle when the drag links 22 have been swung slightly above the pivots 20, or as understood by those familiar with self-locking toggles, "beyond center", by which arrangement the stop 23 is held in contact by 85 said coil spring and the jaws of the device are permitted to remain in open position for removing or inserting the sponge 9, or other 90 mopping material.

As the toggle 19 is again swung to the 95 position indicated in Fig. 2 the forward coil of the coil spring 18 rides the stems 13 in closing the jaw 12 toward the stationary 100 jaw 4, which thus closes upon the sponge or other mopping material as desired.

While the description and drawings illustrate in a general way certain instrumentalities which may be employed in carrying the invention into effect, it is evident that many modifications may be made in the various details without departing from the scope of the appended claims, it being understood that the invention is not restricted to the particular example herein described. 105

What I claim is:

1. In a mop mechanism which removably 110 clamps mopping material in working position, a handle, a relatively stationary jaw extending forwardly of said handle, said jaw being an open frame through which access is had to said mopping material in squeezing and wringing mopping fluid therefrom, a shank formed on said jaw of substantially the same width as said handle and fixed thereto as a continuation thereof, a movable jaw mating with said stationary jaw, said movable jaw also being an open frame through which access is had to the 115 mopping material for squeezing and wringing mopping fluid from the mopping material, another shank mating with the first mentioned shank, formed on said movable jaw of substantially the same width as said handle, the rearward end of said other shank being pivoted to said handle, an expansion spring tensioned between said shanks forwardly of the pivoted end of said other shank, tending to constantly swing 120 said movable jaw pivotally apart from said 125 coil spring. 130

stationary jaw, an expansion coil spring the forward end of which normally surrounds and confines said shanks and the rearward end of which encircles said handle, said coil
5 spring serving to thus normally hold said movable jaw in closed position with said stationary jaw for retaining the mopping material in working position, and a toggle lever means, one end of which is pivoted to
10 said handle and one end of which engages the forward end of said coil spring, said lever means serving to correspondingly compress said coil spring when collapsed and withdraw the forward end thereof from said
15 shanks and thus permit said movable jaw to be swung to open position by the first mentioned spring, said toggle means being foldable upon itself in self-locking position to retain said coil spring in compressed position
20 when the operator wishes to leave said jaws in open position.

2. In a mop mechanism which removably clamps mopping material in working position, a handle, a relatively stationary jaw
25 extending forwardly of said handle, a shank formed on said jaw of substantially the same width as said handle and fixed thereto as a continuation thereof, a movable jaw mating with said stationary jaw, another shank mating
30 with the first mentioned shank, formed on said movable jaw of substantially the same width as said handle, the rearward end of said other shank being pivoted to said handle, an expansion spring tensioned
35 between said shanks forwardly of the pivoted end of said other shank, tending to constantly swing said movable jaw pivotally apart from said stationary jaw, a surrounding means which normally confines said
40 shanks serving to thus normally hold said movable jaw in closed position with said stationary jaw for retaining the mopping material in working position, and a toggle lever means, one end of which is pivoted to said
45 handle and one end of which engages said surrounding means serving to correspondingly withdraw said surrounding means, when collapsed, from said shanks and thus permit said movable jaw to be swung to
50 open position by said spring, said toggle means being foldable upon itself in self-locking position to retain said surrounding means in withdrawn position when the operator wishes to leave said jaws in open position.

55 In testimony whereof, I have hereunto set my hand on this the 3rd day of October, 1931.

EDWIN J. MILLER.
